UNITED STATES PATENT OFFICE.

EDWARD F. REDIES AND RICHARD M. VAN VALKENBURGH, OF KANSAS CITY, MISSOURI, ASSIGNORS TO IRVING-PITT MANUFACTURING COMPANY, OF KANSAS CITY, MISSOURI, A CORPORATION OF MISSOURI.

BOOK HOLDER.

Application filed June 28, 1926. Serial No. 119,230.

This invention relates to a novel book holder and has for one of its objects the provision of a device especially adapted to cover telephone books, magazines or the like which is effective in its operation, durable, cheap to make and not likely to get out of order.

Another object of this invention is to provide a flexible means for engaging between the leaves of the book to be held, which flexible means is locked in place in such a way that it will not accidentally slip from the operative position.

Many minor objects of the invention will appear during the course of the specification referring to the accompanying drawing in which:

Figure 1 is a perspective view of a book holder made in accordance with this invention.

Fig. 2 is a longitudinal central section through the back plate of the holder.

Fig. 3 is an end view of the back plate showing the locking lug in the open position and ready to receive one end of the cable, and,

Fig. 4 is a similar view showing the locking lug in the cable holding position.

As is customary in devices of this character, the invention contemplates the use of a flexible back 5 which has affixed thereto a metal 6, which is secured to the back 5 by rivets or analogous means 7. The novel features of this invention lie in the metal and co-acting parts which perform the function of securely holding the book or magazine between covers 5. Metal 6 should have its ends turned upwardly at right angles to present an arcuate end member 8 between which the book is positioned and which supports a flexible holding cable 9.

There is an up-turned end member at each end of metal 6 and one of the members 8, has an opening through which cable 9 passes to be engaged by a ball or similar member 10 as shown in Fig. 2. One end of cable 9 is adapted to removably engage the adjacent end member 8, and has means carried thereby for coming into actual engagement with the end member 8 to preclude any wearing of the cable 9. The means carried by the free end of cable 9 may be any suitable gripping unit 12 which has a cylindrical protuberance 12' adapted to engage the slot 13 formed in the end member 8. This protuberance 12'

forms a protecting wall around that portion 55 of the cable passing through slot 13, and an annular flange 14 forms a wall which keeps the cable from pulling the gripping member 12 through slot 13 when back 6 is slightly flexed. A ring 15 should be provided to be 60 used as a means for hanging the book holder after the book has been inserted therein. As shown in Figs. 3 and 4, slot 13 is angled slightly and terminates in a portion 13' which extends at right angles to the base of 65 member 6.

After the cable is drawn tight and the gripping member 12 is positioned as shown in Figs. 1 and 2, with protuberance 12' protecting cable 9, the same may be locked in 70 position through the use of a locking means which is here shown to be lug 14 pivotally mounted as at 15 on the slotted end member 8. When the lug 14 is in the unlocked position, it is disposed as shown in Fig. 3 and 75 when it is swung to the closed or locked position, it engages a portion of protuberance 12' and passes between flange 14 and the end member 8. In closing lug 14, its tapered edge 16 wedges into position, and, besides locking the gripping member 12 in place, cable 9 is pulled longitudinally and further tightened. This pulling will slightly flex or bow base metal 6 which will thereafter tend to exert a pressure against cable 9 to hold 80 it taut.

It will thus be seen that when cable 9 has been passed between the leaves of a book, at substantially the center thereof, the parts are rigid and will not jar to the loosened 90 condition. Edge 17 may be arched as shown in Figs. 3 and 4 to further keep gripping member 12 from dropping along slot 13'.

Having thus described our invention, 95 what we claim is:

1. A book holder comprising a semi-rigid back piece having up-turned ends, a flexible member joining said ends and means for tightening said member to slightly flex said 100 back piece.

2. A book holder comprising a semi-rigid back piece having lugs adjacent each end, a flexible member joining said lugs and means carried by one of said lugs for tightening said member and slightly flexing said 105 back piece.

3. A book holder comprising a semi-rigid

back piece having up-turned lugs adjacent each end, a flexible member joining said lugs and means for tightening said flexible member.

5. 4. A book holder comprising a semi-rigid back piece having lugs adjacent each end, a flexible member pivotally connected at its one end to one of said lugs and adapted to removably engage the other of said lugs 10 and means for locking said removable end in the lug-engaging position.

5. 4. A book holder comprising a semi-rigid back piece, a flexible book-engaging cable, means adjacent each end of said back piece 15 for engaging each end respectively of said cable and means for tightening said cable and slightly flexing said piece after said cable has engaged the engaging lugs.

6. A book holder comprising a semi-rigid 20 back piece, a flexible book-engaging cable, spaced apart means integral with said back piece for engaging said flexible cable and means carried by one of said spaced apart means for further tightening said cable 25 after it has been brought into engagement with the engaging means.

7. A book holder comprising, in combination with a pair of covers, a back piece, up-turned lugs integral with said back piece, 30 a flexible cable having its one end pivotally

engaging one of said lugs, a gripping member carried by the other end of said cable and removably engaging the other of said lugs, said gripping member having a protecting protuberance surrounding said cable 35 at the point where it passes through said up-turned lug.

8. A book holder comprising a back piece, spaced apart upturned lugs integral with said piece, a flexible cable having its one 40 end engaging one of said lugs, the other end of said cable having a gripping member adapted to protect said cable at the point where it passes through said other lug and a locking lug mounted on said last-mentioned lug movable into and out of engagement with said gripping member.

9. In a book holder of the class described a flexible cable, a slotted lug adapted to receive one end of said cable and means for maintaining that end of the cable in position in said slot including a pivotally mounted lug having one of its edges arched to preclude movement of said cable along the slot of said lug.

In testimony whereof, we hereunto affix our signatures.

EDWARD F. REDIES.

RICHARD M. VAN VALKENBURCH.
